CLAIM

The ornamental design for a safety shoe, as shown and described.

DESCRIPTION

FIG. 1 is a right side view of a safety shoe showing the new design;

FIG. 2 is a front view thereof;

FIG. 3 is a left side view thereof;

FIG. 4 is a rear view thereof;

FIG. 5 is a top view thereof; and,

FIG. 6 is a bottom view thereof.

The broken lines shown in the figures are for the purpose of illustrating portions of the safety shoe that form no part of the claimed design.
